SKI SCOOTER

Charles F. Molzen and Hangwind F. Lippisch, Wooster, Ohio, assignors to Rubbermaid Incorporated, Wooster, Ohio

Filed Sept. 23, 1970, Ser. No. 25,157

Term of patent 14 years

Int. Cl. D21—02

U.S. Cl. D34—15

The single figure is a perspective view of a ski scooter, showing our new design, the opposite side being substantially a mirror image thereof.

We claim:

The ornamental design for a ski scooter, as shown and described.
